Primary Examiner — Carla J Wright(74) *Attorney, Agent, or Firm* — Shen Huang(57) **CLAIM**

The ornamental design for a mobile phone case, as shown and described.

DESCRIPTION

FIG. 1 is a front elevation view of a mobile phone case, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof, but shown in a fully extended configuration to illustrate the interior;

FIG. 8 is a rear elevation view thereof, but shown in the fully extended configuration for clarity of illustration;

FIG. 9 is a perspective view thereof, but shown in an alternative configuration for clarity of illustration; and

FIG. 10 is another perspective view thereof, but shown in the alternative configuration for clarity of illustration; and,

FIG. 11 is a perspective view thereof, but shown in another alternative configuration for clarity of illustration.

The short dashed broken lines in the drawings depict unclaimed portion of the phone case only and form no part of the claimed design. The long dashed broken lines disclose stitching which forms part of the claimed design.

1 Claim, 11 Drawing Sheets(56)
